FRAME FOR A MIRROR

Sydney Cash, 496 Avenue of the Americas,
New York, N.Y. 10011

Filed Aug. 6, 1969, Ser. No. 18,554

Term of patent 3½ years

Int. Cl. D6—06

U.S. Cl. D29—20

FIG. 1.

FIG. 5.

FIG. 2.

FIG. 3.

FIG. 4.

FIG. 1 is a front perspective view of a frame for a mirror showing my design;

FIG. 2 is a front elevational view thereof;

FIG. 3 is a rear elevational view thereof;

FIG. 4 is an elevational view of the longer side thereof;
and

FIG. 5 is an elevational view of the shorter side thereof.

I claim:

The ornamental design for a frame for a mirror, substantially as shown.
